[57] CLAIM

The ornamental design for a combined rack and picture frame, as shown and described.

DESCRIPTION

FIG. 1 is a top, front, and left side perspective view of a combined rack and picture frame showing my new design;

FIG. 2 is a front elevational view thereof;

FIG. 3 is a rear elevational view thereof;

FIG. 4 is a left side elevational view thereof, the right side being a mirror image of that shown;

FIG. 5 is a top plan view thereof; and,

FIG. 6 is a bottom plan view thereof.

The broken-line disclosure of a baseball in the views is for illustrative purposes only and forms no part of the claimed design.
